UNITED STATES PATENT OFFICE.

DENIS FRANCIS BRESLIN, OF JOHANNESBURG, TRANSVAAL.

DREDGING APPARATUS.

SPECIFICATION forming part of Letters Patent No. 739,382, dated September 22, 1903.

Application filed July 13, 1903. Serial No. 165,300. (No model.)

To all whom it may concern:

Be it known that I, DENIS FRANCIS BRESLIN, a citizen of the United States, residing at Johannesburg, Transvaal, South Africa, have **5** invented certain new and useful Improvements in Dredging Apparatus, of which the following is a specification.

This invention relates to a dredging plant or apparatus applicable for dredging in harbors, **10** rivers, canals, or other watercourses, on bars or other silts or shoals at the mouths of or in rivers or harbors, or in other places where the deposit or spoil to be removed consists of sand, mud, or the like which is immersed or **15** under water. The apparatus may be used for the purpose of removing the silts, shoals, or deposits to deepen the watercourse, with the object of maintaining or rendering it navigable. It may also be readily adapted **20** for dredging river-beds to recover auriferous or other deposits or for any other analogous purpose.

The invention consists, essentially, in the peculiar construction and arrangement here-**25**inafter particularly described of what I may term the "eroder"—that is to say, that part of the apparatus which operates directly upon the deposit or spoil to effect the removal of the same—and, further, to the general construction and arrangement of the whole apparatus.

The invention will now be described in detail by aid of the accompanying drawings, wherein I illustrate the adaptation of the same **35** for use under three different conditions, in which—

Figure 1 shows the apparatus in elevation as adapted for dredging in places where the whole of the apparatus would require to be **40** afloat. Fig. 2 is a plan of Fig. 1. Fig. 3 is an elevation of the apparatus adapted for dredging in a river, canal, or other watercourse, or under conditions which would allow of the apparatus being supported and operated from both banks of the course. Fig. **45** 4 shows an arrangement of the apparatus for operating on a bar or shoal and operated from shore; and Fig. 5 is a view of a portion of the eroder, illustrating the construction of the **50** same.

Referring to the arrangement illustrated in Figs. 1 and 2, which arrangement is specially

applicable for dredging in harbors or under any conditions that would require the whole of the plant or apparatus to be afloat, A B C **55** represent three pontoons, which may be constructed of suitable material and be of any suitable design and dimensions according to the requirements. The several pontoons are connected by means of the removable bridging **60** or gangways D. In some cases the intermediate pontoon B could be dispensed with and the pontoons A C only be used and be connected by means of the bridging or gangways D in the same manner, or any number of pontoons **65** may be arranged between the two end pontoons A C to meet any special requirements or circumstances.

The eroder, or that portion of the apparatus which operates directly on the silt or deposit to remove the same, is indicated by the letter E. As is indicated in Fig. 5, it comprises a core or center F of a flexible cable-laid or other suitable wire rope, around which are arranged spiral metal plates or blades G, **75** which form the continuous screw or helical blade H around the core. The metal plates or blades G are made of spring-steel or other suitable metal which will give the requisite strength and flexibility to permit the eroder **80** to assume the requisite curvature when working. The ends of the adjacent spiral plates or sections of the helical blade are bolted or riveted together, as is indicated at h' in Fig. 5. Each section of the spiral blade or screw **85** H is fixed to the flexible core F by means of one or more of the clamps I. (See Fig. 5.) To obtain the maximum efficiency, the pitch of the helical blade or screw H is equal or approximately equal to sixteen times the diameter of the flexible core F. The eroder is suspended from the two end pontoons A C in such manner that it can be raised above or lowered upon the silt or deposit or to the bed of the river or other watercourse, as is shown **90** in Fig. 1. The manner of raising, lowering, and operating the eroder will be hereinafter described. In the pontoon A is placed the requisite power-plant for driving the eroder and propelling the apparatus. To the outside of the pontoon A are suitably fixed one or more pairs of slide-rails K, which form a guideway or guideways projecting outward from the end of the pontoon. In the slide- **95** **100**

rails is arranged a platform *k*, which is capable of being traversed in the guideways longitudinally thereof by means of an adjusting-screw *L*, which works through a nut or internal screw-thread formed in the under side of the platform. On the platform is arranged an electric motor, engine, or other suitable means *M* for transmitting power to the eroder. On the outer extremity of the main shaft *M'* of the motor or engine *M* is fixed a bevel-wheel *N*.

On the under side of the traveling platform *k* are formed or fixed two brackets or hangers *O*, in which is journaled an obliquely-arranged driving-shaft *P* for the eroder. The shaft *P* is provided with thrust roller-bearings *R*, and on the extremity of said shaft is fixed a bevel-wheel *n*, which gears the bevel-wheel *N*. The slide-rails *K* are stayed by means of two stays or braces *k'*. One extremity of the flexible core *F* of the screw *H* is attached to the end of the shaft *P* by means of the coupling *p*. In the bottom of the pontoon *A* a recess is formed to accommodate the upper portion of the flexible core *F* of the screw *H*. The other end pontoon *C* serves to carry the mechanism for raising and lowering the eroder. It is constructed with one or more arched and tapered recesses *c*, in each of which is arranged a trough-shaped collector *h* for the deposit or spoil raised by the eroder. The trough *h* is arranged around the eroder at the upper or delivery end. The trough may be made in one or more sections, as may be most convenient, and the sections be joined to each other by a hinged or other suitable joint which will allow it to conform to any curvature of the eroder *H* and to allow of its being raised or lowered to varying depths.

On the upper extremity of the trough-collector *h*, beyond the end of the pontoon *C*, is formed or securely fixed a bracket *c'*, which forms a support for the extremity of the eroder and spoil-collector. The bracket *c'* is capable of vertical adjustment on guide-rails at the side of the pontoon *C*. The vertical adjustment is obtained by means of the vertically-arranged square-threaded screw *c²*, fixed to the bracket *c'*, which screw *c²* projects through a pedestal *c³*, carried by the pontoon, and is fitted with a nut or hand-wheel *c⁴* for raising and lowering the screw *c²*, and with it the bracket *c'*, trough or collector *h*, and eroder *H*. In the bracket *c'* is a horizontally-arranged square-threaded screw *d*, which is connected with the end of the eroder by means of a swivel *d'*. The screw *d* is fitted with roller thrust-bearings *d²* to take up the thrust and with a nut or hand-wheel *d³* for moving the screw horizontally in the bracket *c'* in either direction. Means are thus provided for effecting any desired adjustment of the eroder and spoil-collector in either a horizontal or vertical plane. The intermediate portion or section of the trough or spoil-collector *h* is supported and adjusted

vertically by an arrangement comprising a screw *e*, which is attached at its lower end to the trough *h* by means of a chain and bail or bridge-piece *e'*, spanning the top of the trough. The screw projects through a pedestal *e²* and is fitted with the nut and hand-wheel *e³* above the pedestal, which allows of the screw *e* being raised or lowered, as required. The lower portion or section of the trough *h* is supported and adjusted in a vertical plane by means of the bail *f*, spanning the top of the trough, and the chain *f'*, attached to said bail. The chain *f'* is wound around the drum *f²* of a winch carried by the pontoon *C*.

The eroders will be raised or lowered, as may be required, to correspond with variations in the tide in order to preserve a channel of uniform width throughout by means of the above-described arrangements, which may be manipulated by manual or other power. The eroder is preferably raised or lowered by the means controlled by the screw *d* when dredging. The three vertically-disposed adjusting-screws are used for lowering and raising the trough or spoil-collector to effect any requisite adjustment of the latter in relation to the eroder.

In Figs. 1 and 2 of the drawings I illustrate one eroder disposed centrally of the three pontoons *A B C*. Two other eroders may be employed arranged parallel with the one shown and be located at the sides of the several pontoons *A B C*, as is indicated by the chain-lines 1 1 and 2 2 in Fig. 2. These additional eroders would be arranged, driven, and manipulated in a similar manner to that described. The two end pontoons *A C* are provided at the bottom and preferably at both sides with eroders *S* for providing a channel for continuously floating said pontoons, if required. These eroders *S* may be of the construction hereinbefore described, or they may be formed on a non-flexible straight bar or core. They may be driven from the bevel-gearing *S'* by means of a separate motor or otherwise, as may be preferred.

The operation of the apparatus may be described as follows: The apparatus is first brought in position over the place where the dredging is required to be performed and the eroder (or eroders) is lowered to the bottom. The eroder is then rotated at a speed or velocity by the motor *M* through the bevel-gearing *N n*, the shaft *P*, and coupling *p*, the swivel *d'* permitting the other extremity to revolve freely round its point of attachment with the screw *H*. This rapid rotation of the eroder agitates the surrounding water to such an extent that it assumes the nature of a vortex traveling parallel with the axis of the eroder, and all sand, mud, or the like lying within the influence of this vortex is disintegrated and carried along by the velocity of the water assisted by the eroder up the trough or spoil-collector and delivered onto the shore or into a barge or any other receptacle placed in position for its reception.

In Fig. 3 I illustrate the apparatus adapted for dredging in a river, canal, or other watercourse. In this case the eroder is supported and operated from the banks. Trucks 5 T T' are employed, which traverse rails laid on the banks. One truck, T , carries the motor M^2 for driving the eroder and the other truck, T' , the roller thrust-bearings and the means for manipulating the eroder and also 10 the spoil-collector h . The spoil-collector is further supported by the pontoon M^3 . The spoil is thrown by the eroder up the collector clear of the bank. In place of the trucks I may attach the eroder to guy-stays similarly 15 or otherwise conveniently placed on the banks.

In Fig. 4 the apparatus is shown as adapted for use on a bar or shoal or in cases where it is considered unnecessary to lift the silt or 20 spoil, but simply to throw it at either side. In the arrangement illustrated two piles O^1 O^2 are employed, to which one extremity of the eroder is attached by the swivel connection o^1 . The piles are driven in in a suitable position and connected by the cross-bar o^2 , to 25 the center of which bar the end of the eroder is connected to prevent the piles offering any obstruction to the removal of the spoil. The motor, engine, or other means o^3 for driving 30 and manipulating the eroder is shown located on the bank or pier o^4 . This arrangement may be used in places where the water flows at a velocity sufficient to cause a scour or carry away the deposit or material.

35 In the two arrangements illustrated in Figs. 3 and 4 the extremity of the eroder is connected or coupled up with the main driving-shaft of the motor through the medium of a suitable coupling-piece o^5 .
40 From the foregoing description it will be obvious that the eroder may be attached either to moving or stationary objects, as the circumstances may suggest, to adapt the eroder terminal attachments and driving appliances 45 to suit individual cases.

What I claim as my invention, and desire to protect by Letters Patent, is—

1. In dredging apparatus of the nature indicated the eroder comprising the flexible core or center round which are secured sectional 50 helical blades forming a flexible continuous screw, substantially as described.

2. In dredging apparatus of the nature specified the eroder or appliance for operating on the silt or deposit to remove the same, 55 consisting of a flexible core or center round which are secured flexible sectional helical plates or blades forming a continuous screw, the pitch of which screw is equal or approximately equal to sixteen times the diameter of 60 the core, substantially as and for the purposes described.

3. In dredging apparatus of the nature indicated the combination with the eroder comprising a flexible core of cable-laid or other 65 suitable wire rope, round which core are secured flexible sectional helical plates or blades forming a continuous screw, of the spoil-collector arranged round the delivery end of said screw, and means for adjusting and manipulating the eroder and spoil-collector, substantially as and for the purposes described.

4. In dredging apparatus of the nature indicated the combination with the eroder consisting of the flexible core of a suitable wire 75 rope and the flexible sectional blades forming the continuous screw of the trough or spoil-collector arranged round the delivery end of the eroder, the means for adjusting and manipulating the eroder and spoil-collector and the means for driving the eroder at a high speed, substantially as and for the purposes described.

In witness whereof I have hereunto set my hand in the presence of two subscribing witnesses.

DENIS FRANCIS BRESLIN.
